UNITED STATES PATENT OFFICE.

JOHN BOOTH, OF INDIANAPOLIS, INDIANA.

SLIDE-VALVE.

SPECIFICATION forming part of Letters Patent No. 339,734, dated April 13, 1886.

Application filed September 14, 1885. Serial No. 177,017. (No model.)

To all whom it may concern:

Be it known that I, JOHN BOOTH, a citizen of the United States, residing at Indianapolis, in the county of Marion and State of Indiana, 5 have invented a new and useful Improvement in Slide-Valves for Steam-Engines, of which the following is a specification.

My invention relates to improvements in slide-valves for steam-engines; and the objects 10 of my improvements are to relieve the surface of the valve from the friction consequent on the difference of pressure between the back of the valve and the cavity of the exhaust or eduction passage. This I attain by means of 15 construction as illustrated in the accompanying drawings, in which--

Figure 1 is a top view of the valve and steam-chest with the cover removed; Fig. 2, a vertical longitudinal section through the center. Fig. 3 is a front end elevation of the valve; Fig. 4, a vertical transverse section of the valve through the line 1 2.

Similar characters of reference apply to similar parts in the several views.

25 A is the slide-valve; B, the equalizing frame or ring; C, the elastic packing; D, the packing frame or ring. E E are the packing-springs. F F, &c., are the steam-vents. H is the valve-yoke; I, the valve-rod; J, the steam-chest; K, the valve-seat. L L are the steam-induction ports. M is the steam exhaust or eduction port. N is the steam-chest cover; O, the exhaust-pipe. a a, &c., are the steam-chest bolts; c, the packing-groove.

35 The mode of constructing and operating my improved valve is as follows: The valve A in external outline is a plain rectangular body of dimensions suitable to the induction-ports L L, and is enveloped by the yoke H, 40 to which is attached the valve-rod I, by which the valve is operated. The exhaust or eduction cavity extends through the whole depth of the valve. The packing-groove c is formed in the walls of the valve between the outside 45 and the exhaust-cavity. The equalizing frame or ring B is fitted to the packing-groove c, and

extends above the top of the valve A, with an outside dimension corresponding to the valve. The packing frame or ring D is fitted to the groove c, and is supported by the packing-springs E E and sustained above the steam-vents F F, &c., which admit the steam and press the frame D toward the equalizing-frame B. The space between the equalizing-frame B and the packing-frame D is filled by a body of 55 fibrous material—such as asbestos—as will retain its elastic properties without deterioration from the action of the heat of the steam. By the pressure of the steam acting on the packing-frame D and compressing the packing material 60 C C the steam cannot escape beyond the equalizing frame or ring B, and it is consequently forced outward against the steam-chest cover N, thereby making the upward-pressed surface of the equalizing-frame B equal to the 65 downward-pressed surface of the valve A, minus the area of the space between the packing-groove c and the outside of the walls of the valve A, thus leaving a preponderance of 70 pressure in favor of the valve to secure its adhesion to its seat K.

The packing frame or ring B can be made of a circular form and the packing-groove in the back of the valve made to conform thereto; or it can be made of a rectangular shape and correspond to the shape of the ordinary slide-valve.

I do not claim the equalizing frame or ring B, the grooved-back valve A, the springs E E, nor the steam-vents F F, &c.

80 What I claim, and desire to secure by Letters Patent of the United States, is—

In a slide-valve of a steam-engine, the packing frame or ring D, in combination with the equalizing frame or ring B, the packing-groove 85 c, packing C, springs E E, and steam-vents F F, &c., substantially as described, and for the purpose as set forth.

JOHN BOOTH.
